UNITED STATES PATENT OFFICE

FRANK S. TRUSLER, OF VERNON, TEXAS

ARTIFICIAL TOOTH

Application filed February 2, 1929. Serial No. 336,969.

This invention relates to an artificial tooth structure for dental work and it has more particularly reference to the specific subclass embodying porcelain facing preferably mounted on metallic backing plates through the medium of a pin and socket connection.

In carrying out this invention I have evolved and produced a structure which is characterized by a special design of coupling 10 means between the plate and facing and so made as to provide for more efficient and dependable action and to better fulfill the requirements of an assemblage of this class.

The specific features distinguishing the 15 improved coupling will become more readily apparent from the following description and drawings.

In the drawings:

Figure 1 is a group perspective view showing the backing plate and special coupling members associated therewith.

Figure 2 is a vertical sectional view through the complete tooth showing the members coupled together.

Figure 3 is a view at right angles to Figure 2, the section being taken on the vertical line 3—3 of Figure 2.

Referring now to the drawings by reference numerals, it will be seen that 4 designates a porcelain facing having a gum shield extension 5 at one end, while the reference character 6 designates the metallic backing plate.

The facing 4 has a vertically elongated 35 substantially ovate cavity formed therein, which under normal conditions is apt to contain a quantity of cement for holding the female coupling member 8 in place. This member 8 is of peculiar configuration and 40 made of appropriate metal and fashioned to form a two-way socket casing as clearly shown in Figure 1. In other words, this member is so designed as to provide an upper socket 9 communicating with the correspondingly shaped lower socket 10, these 45 sockets being of split form to render them sufficiently resilient for a desirable snap coupling action. A continuous anchoring rib is designated by the reference character 11 and 50 this projects outwardly in the manner shown,

in order that it may be embedded in the cement for proper maintenance of the part 8. In addition, the individual sockets 9 and 10 are formed with segmental lips or flanges 12, functioning as resilient retaining shoulders. These extend inwardly as shown in Figure 2. The male coupling member 13 is formed integral with the backing plate 6 and said male coupling member comprises an upper substantially cylindrical portion 14 adapted to fit in the socket 9 and a lower substantially cylindrical part or portion 15 adapted to fit in the socket 10.

A solid web portion 16 joins the pins. Both pins are formed adjacent their inner ends with outstanding circumferential ribs 17 adapted to snap behind the segmental shoulders 12. In addition, there is an outstanding marginal flange 18, functioning as a spacer when fitted into the socket as shown in Figure 2. With this arrangement suitable space is left between the adjacent surfaces of the parts 8 and 13 to accommodate a retaining cement and when the parts are assembled as seen in Figure 2, a rigid and 75 dependable type of joint is had.

From a study of Figure 1, it will be noted that the female coupling member 8 has the upper and lower socket portions provided with horizontal slits 19 to permit expansion and contraction of the socket. It is to be further noted, that the sockets 9 and 10 intercommunicate through the medium of a connecting channel 20, and the side walls of the channel 20 are notched as at 21 to permit of a longitudinal expansion or contraction of said female member.

The advantages and features of a joint of this kind will be clear to persons skilled in the art to which the invention relates after 90 considering the description in conjunction with the drawings. Therefore a more lengthy description is regarded as unnecessary.

Minor changes in the shape, size, and rearrangement of details coming within the field 95 of invention claimed may be resorted to, in actual practice, if desired.

I claim:

1. In an artificial tooth structure of the class described, a facing having a cavity 100

adapted to receive an expansible female coupling member, said female coupling member comprising upper and lower sockets and a restricted vertical channel between the sockets communicating with the sockets, a backing plate cooperable with said facing and having an integral male coupling member embodying upper and lower substantially cylindrical portions receivable in said sockets and a vertical web connecting said substantially cylindrical portions and receivable in said channel.

2. In an artificial tooth structure of the class described, a facing having a cavity adapted to receive a female coupling member, said female coupling member comprising upper and lower sockets and a vertical channel between the sockets communicating with the sockets, a backing plate cooperable with said facing and having an integral male coupling member embodying upper and lower substantially cylindrical portions receivable in said sockets and a vertical web connecting said substantially cylindrical portions and receivable in said channel, the entrance portions of said sockets being provided with segmental retaining shoulders, and said male member being provided with an outstanding spacer flange at the forward end thereof cooperating with the internal surface of the walls of said sockets and channel.

3. In an artificial tooth structure of the class described, a facing having a cavity lined with cement, a female coupling member arranged in said cavity and embodying an elongated body formed into upper and lower spaced communicating resilient retaining sockets and a channel extending between and communicating with said sockets, the entrance portions of said sockets being provided with segmental retaining shoulders, and said body having a continuous outstanding anchoring rib embedded in said cement, a backing plate having an outstanding integral male coupling member embodying upper and lower substantially cylindrical portions and a connecting web merging at its opposite ends into said cylindrical portions, the upper and lower cylindrical portions of said male member adapted to be received in the sockets of said female member and said web adapted to be received in the channel of said female member, retaining ribs formed on the cylindrical portions of said male member engageable with said shoulders, and said male member being further formed with a continuous outstanding spacer flange cooperating with the internal surface of the aforesaid body.

4. In testimony whereof I affix my signature.
FRANK S. TRUSLER.
